AUGUST REGAL, OF BANJALUKA, AUSTRIA-HUNGARY, ASSIGNOR OF ONE-THIRD TO FRANJO HARAZIM AND ONE-THIRD TO EUGEN KARAZEJ, OF BANJALUKA, AUSTRIA-HUNGARY.

APPARATUS FOR WEAVING IN NATURAL COLORS WITHOUT PATTERN-CARDS.

No. 873,683.

Specification of Letters Patent.

Patented Dec. 10, 1907.

Application filed June 11, 1906. Serial No. 321,248.

To all whom it may concern:

Be it known that AUGUST REGAL, professor, a subject of the Emperor of Austria-Hungary, residing at Banjaluka, Bosnia, 5 Austria-Hungary, has invented certain new and useful Improvements in Apparatus for Weaving in Natural Colors Without Pattern-Cards; and he does hereby declare the following to be a full, clear, and exact description of the invention, such as will enable others skilled in the art to which it 10 pertains to make and use the same.

This invention relates to an application to the art of weaving of the process used in 15 three color printing, for the purpose of obtaining correct woven reproductions of natural objects or pictures. For this purpose first, negatives of the three single color partial pictures are prepared as in the three 20 color printing process by photographing the article to be reproduced, the said negatives being made in red, (purple red) yellow and blue (green blue) by the use of light filters and from these negatives single color partial 25 positives are printed, by means of the well known chromate process, on three plates made of insulating material (glass, porcelain, vulcanized rubber) and galvanically coated with metal. The portions of the partial 30 pictures which have not been exposed to light, are electrically conducting after the plates have been washed and slightly etched, the portions exposed to light remaining covered with chromium oxid gelatin, that is to 35 say non-conducting.

In the three-color printing process, the printing plates or blocks are covered by means of rollers, with printing inks of the three fundamental colors, and the partial 40 pictures printed on the top of each other, whereby a combined picture in natural colors is obtained, as the three fundamental colors, as is well known, are sufficient for reproducing any shades and gradations of color to be 45 found in pictures or in nature. A picture produced by the three-color printing is constituted throughout by points, most of which show combined colors. They are those points in which the paints of two or 50 three fundamental colors coincide, which is generally called "color subtraction". To the naked eye, the multitude of colored points forms one harmonious whole, and by "color addition" produces the natural im-

pression of the original from which the partial photographs were taken.

In the present invention according to which a picture is to be woven from threads the combination colors cannot be produced by color covering or subtraction as the threads are not transparent. But it is possible to arrange in the warp threads of combined colors, to employ these as well as threads of the fundamental colors and to allow them to act on the spectator by color 65 addition alone, as in a printed three-color picture. The points of the pictures produced by the three color printing process are replaced in the woven fabric by corresponding points of intersection and therefore the 70 apparatus according to this invention is applied to a wire loom of well known construction.

In addition to the warp threads of the three fundamental colors, red, yellow, and 75 blue, there are also provided threads of orange, violet, green (combinations of two colors), black and white (combinations of three colors) and a pile warp is used for each color so that altogether, in addition to the 80 ground warp, there are eight pile warps. In accordance with the pile warps the hooks used in the loom are arranged in eight series, each of which contains as many hooks as there are pile warp threads to be woven into 85 the fabric in the direction of its width, as each of such pile warp threads is connected to one hook. From this series of threads, the proper pile warp thread is raised at given moments for forming the upper shed. The 90 hooks are raised by means of narrow lifting blades arranged on bars which are moved by a driving arm by means of a "receiver" or device operated by an electromagnet, the said bars remaining in the position corresponding to the extent of movement of the driving arm, the extent of such movement being capable of being regulated by the receiver. In order to enable all the bars with 95 their blades to be moved, the receiver with the driving arm is moved longitudinally in front of the columns of hooks the driving arm returning again to its original position after every operation, before it acts on the next bars.

The action of the receiver is determined by the "transmitter" of the device, which consists of the three already described plates

arranged side by side in one frame, but electrically insulated from each other. On the first plate all those points act as conductors which reproduce the portions of the 5 total picture, which have been photographed with the green filter, on the second plate those which have been photographed with the violet filter, and on the third plate, those which have been photographed with 10 the orange filter, while the remaining portions of the plates are covered with chromium oxid gelatin, that is to say, are non-conducting. On each of the plates slides a contact pin; the contact pins are provided 15 with a common guide, but are electrically insulated from each other, and move synchronously with the receiver. Each of the three transmitter plates is connected to one pole of a source of current, the second pole of 20 which is connected to the plate above which the receiver slides. The plate is made of insulating material and contains series of contacts which are arranged in such a manner that the columns of contacts lie in the 25 plane of the columns of hooks. The source of current is connected to the second, fourth, sixth series of contacts, and the contact pins of the transmitter plates to the third, fifth and seventh series of contacts. When a contact 30 of the third series of contacts is connected by a bridge to an opposite contact of the fourth series, the source of current, in the event of the contact pin switched into the circuit touching a conducting point of 35 the corresponding transmitter plate, sends a current through the bridge. The same thing happens when the fourth and the fifth series of contacts, and the sixth and seventh series of contacts, are connected together by 40 a bridge and the corresponding contact pins touch the conducting points of the corresponding transmitter plates. The bridges are constituted by the electromagnets of the receiver, which operate the latter with the 45 driving arm, so that the blades should come under the corresponding hooks and raise them. If, for instance, the contact pin of the plate for the red partial picture, touches a conducting point of the same, while the 50 two other contact pins are on non-conducting points of the corresponding plates which means that the corresponding point of the original emits only red rays, then a binding point must be formed in the fabric by means 55 of a red thread. The current emitted by the source of current flows through the first transmitter plate, passes into the first contact pin, flows through the windings of the electromagnet constituting the bridge of the 60 corresponding series of contacts of the receiver plate, and returns to the source of current. Owing to the action of the electromagnet, the mechanism directly operating the driving arm, becomes operative and 65 advances the bar carrying the blade to such

an extent that the blade arrives under a hook carrying a red pile warp thread which, when the hook is raised, is brought into the upper shed. The advanced driving arm returns to its original position before the receiver arrives in front of the next column of hooks, so that the device is ready for advancing the next bar. 70

In the accompanying drawings is shown by way of example a construction of apparatus according to this invention as applied to a wire loom of known construction. 75

Figure 1 is a side elevation, Figs. 2 and 3 a front elevation, and Fig. 4 is a plan of the apparatus applied to a weaving loom, Fig. 5 is a front elevation and Fig. 6 a side elevation of the receiver, while Fig. 7 is a detail of the same. Figs. 8 and 9 show the frame for the transmitter plates in plan and in side elevation, and Figs. 10 to 12 show a portion of the frame with the transmitter plates and contact pins in plan, front elevation and side elevation. Fig. 13 is a plan, and Fig. 14 a front elevation of the transmitter, and Figs. 15 to 17 show details of the same on a larger scale. Fig. 18 shows the contact plate of the receiver and Fig. 19 a contact bar and its position relatively to the bars carrying the blades. Figs. 20, 21 and 22 are respectively a plan, a front- and side-elevation of the loom driving gear, from which the apparatus in question is driven. Fig. 23 shows the hook lifting device in front elevation, Fig. 24 is a section on the line M—N of Fig. 23. Fig. 25 is a hook or hooked wires in front and side elevation. Fig. 26 is a grating for guiding the hooks, in perspective view and Fig. 27 is a diagrammatic view of the electric connections. Figs. 28 and 29 are semi-diagrammatic views respectively showing the circuit conditions and the relative positions of the essential parts when a red warp thread is called and when a green warp thread is called. 90

On a counter-shaft 1 of the weaving loom, which is driven by means of a suitable transmission from a source of power, is mounted a pulley gear consisting of a fast pulley 2 and loose pulley 3, and two spur wheels 4 and 5 (Figs. 20, 21 and 22). The toothed wheel 4 is provided with teeth only on four-fifths of its circumference and the wheel 5 only on one-fifth of its circumference, the teeth being arranged in such manner that they are opposite the smooth portion of the circumference of the toothed wheel 4, that is to say, the teeth of the wheel 5 form the missing fifth of the teeth of the wheel 4. The wheel 4 engages with a toothed wheel 6 mounted on a spindle 6' and the wheel 5 with a wheel 7 mounted on the main shaft 11 of the weaving loom. The toothed wheel 6 is secured to a bevel wheel 8 driving a bevel wheel 9 mounted on a spindle 9'. The ratio between the wheels 4 and 6 is such, that the wheel 6 110

makes half a revolution while the wheel 4 makes four-fifths of a revolution. As the bevel wheels 8 and 9 are equal, the bevel wheel 9 also makes half a revolution in the 5 same time. On the wheel 9 is mounted a pin 10' on which is pivoted a rod 10. The ratio of the wheels 5 and 7 is such that the wheel 7 makes a whole revolution when the wheel 5 makes one-fifth of a revolution. 10 While the counter-shaft 1 makes four-fifths of its revolution, the bevel wheel 9, owing to the engagement of the wheels 4 and 6, makes half a revolution. The main shaft 11 of the weaving loom remains, however, standing 15 still as the wheels 5 and 7 do not engage with each other. When the counter-shaft 1 makes the last fifth of its revolution, the wheels 5 and 7 come into engagement with each other, the wheels 4 and 6 become disengaged, so that the bevel wheel 9, and the 20 parts of the loom operated by it, remain standing still, while the loom shaft 11 makes a complete revolution.

The formation of the shed takes place in 25 the well known manner from the loom. The rod 12 operated by a treadle is connected at its upper end to a double-armed lever 13, (Fig. 1), to the other end of which lever is pivoted a link 14 engaging with a spindle 15, 30 by raising which the upper shed is formed. A second link 16 connected to the lever 13 is pivoted to one end of a two-armed lever 17 of which the other end is connected to a link 18 to the carrier of the bottom board 20 of the 35 hooks. The carriers of the bottom board of the hooks are guided by means of guide plates 20' on guide ways of brackets 19 during the raising of the bottom board 20 of the hooks, which takes place at each operation of 40 the lever 13, so that a double shed is then always formed. The hooks raised by the blades raise a portion of the pile threads into the upper shed, while the hooks resting on the bottom board, bring the remaining pile 45 threads into the bottom shed, owing to the raising of the bottom board. Owing to the formation of the double shed, the weft can be simultaneously introduced into the bottom shed, and the wire into the upper shed. 50 The pile threads introduced into the bottom shed, are woven into the ground fabric together with the ground warp which is raised by means of heddles into the bottom shed.

The spindle 15 extends through the ends 55 of rods 21 by means of which it is guided while being raised. The rods 21 are cylindrical in cross-section in their lower portion to engage with bearings 22 provided for their guidance on the loom frame 38, while 60 the upper portion of the rods is rectangular in cross-section in order to enable plates 23 to be secured on both sides thereof, (Figs. 23, 24). The plates 23 serve for supporting bars 24 which are also rectangular in cross-section 65 and with their narrow sides rest on edges

formed by giving a wedge-shaped chamfer to the upper side of the plates 23. The ends of the bars 24 are bent into the shape of a half horse-shoe, one bar being alternately bent downwards, and the next one upwards (Fig. 70 24). At the beginning of the straight portion of each bar its upper edge is provided with teeth 24' while at a small distance from the teeth there is secured a blade 25 for raising the hooked wires or hooks. The number 75 of the bars used is equal to the number of the hooks of one series. For each column consisting of eight hooks there is therefore provided one bar with one blade which becomes operative, when the spindle 15 with the rods 80 21 and the lifting frame constituted by the two plates 23 are raised, and lifts the hook under which it happens to be placed. The arrangement of the bars with blades is such that the latter can be easily moved forwards 85 and backwards between the columns of hooks.

In the normal position all the blades are in one row, as they hang exactly below the projections of the last series of hooks. In order 90 to maintain the bars in their proper position, there are arranged on the plates 23 of the guide frame, two bars 26 and 27 projecting beyond the plates 23 and the upper edge of the said bars are provided at suitable distances 95 with parallel recesses or notches in which the bars 24 are located. In order to enable the plates 26 and 27 to be set exactly, they are secured to the plates 23 by means of bolts 26" and 27", passing through slots 26' and 100 27'. In the rods 21 a spindle 28 is mounted which is provided at its upper flattened portion with a guide for a bar 29 provided with a downwardly bent edge, in which guide the said bar can move but is caused to rotate 105 with the spindle 28. At the ends of the bar 29 are arranged extensions or projections 29' which engage in guide slots in plates 30 provided on the rods 21. The slots of the plates 30 are bent upwards and forwards in such 110 manner that as the bar 29 turns it is moved forward owing to the engagement of the projections 29' in said guide slots. On the spindle 28 is mounted a weighted lever 31, of which the front end is formed as a nose 31', 115 which during the upward movement of the bars 21 for the formation of the upper shed strikes a projection 32' of a fixed bar 32, whereby the weighted lever is caused to turn together with the spindle 28. In this movement the bar 29 is lowered simultaneously 120 moved forward and brought into engagement with the teeth 24' of the bars 24 holding them fast in the position in which they have been in the meantime placed. The 125 movement of the bars 24 is effected as hereinbefore stated, by means of a driving arm operated by the receiver, as will be herein-after fully described. In order to bring these bars 24 back to their normal position 130

during the downward movement of the parts raised for forming the shed, a plate 33 is provided secured to an angle iron. The forked end of one arm 34 of a bell-crank lever is in engagement with a bolt 33' on a lug 33" of the angle iron; the other arm 35 of the lever being provided with an adjustable weight, so that the bell-crank has the tendency to keep the angle iron, together with the 10 plate 33, in the extreme left hand position (Fig. 24). The arm 35 of the bell-crank lever is provided at one end with a nose 35' arranged in front of a fork 36 which is secured by means of a bolt 36' to the rod 21 15 and held in vertical position by means of a spring 36''. During the upward movement of the bar 21, the end of the fork 36 is forced back when it strikes the nose 35' of the lever arm 35 the bell-crank being held in 20 the bracket 37 against further movement towards the left hand of an observer looking at Fig. 24, so that the fork 36 passes into position above the nose 35'. Consequently the angle iron together with the plate 33 remains 25 in position on the top plate 37' of the bracket 37 which plate forms a guide for the plate 33 during its movement. When the rod 21 descends, during the closing of the shed, the end of the fork, which is now above the nose 35', 30 engages therewith and turns the lever 34, 35 moving the angle iron with the plate 33 towards the right, and thus returns the bars 24 to their normal position. When the end of the fork 36 slides off the nose 35', the lever 35 34, 35, owing to the action of the weight, returns back to its original position on the left hand side and carries with it the angle iron with the plate 33.

The hooks 25' constituted by flat strips of 40 metal are bent at the upper end (Fig. 25) to form hooks with which the blades 25 engage. Their lower ends are provided with slots to which the hook strings are attached. As 45 already stated, the hooks are arranged in eight series of which each contains as many hooks as there are pile threads to be woven into the fabric in the direction of its width. To the hooks *w* of the first series (beginning from the right hand side) are attached white 50 pile threads, to the hooks *r j o b v g* and *s* the red, yellow, orange, blue, violet, green and black threads respectively. The hooks are inserted into two gratings arranged one above the other, in order to enable the vertical movement during the formation of the shed, to be executed very exactly. For supporting the gratings two pairs of bars 39 and 40 are employed, arranged one above another and secured to the loom frame 38 (Figs. 55 23, 24 and 26). To the outside of each of the bars is secured, by means of bolts 41' passing through slots a plate 41, the upper edge of which is provided at suitable distances with parallel recesses which afford 60 guidance to the plates 42. Each of the par-

allel plates 42 is situated between two columns of hooks, and in opposite recesses of the plates 41. On the plates 42 are arranged parallel wires 43, each of which is situated between two series of hooks and has 70 its ends secured to the bars 44, arranged on the plates 39 and 40.

The operating of the bars carrying the blades 25 is effected by a special device called the receiver (Figs. 4-7). Rotatably 75 mounted intermediate their ends on a spindle 55, are four levers 59, 58, 57 and 56 each carrying at one end an armature for an electromagnet A, B, C, and D respectively and at the other end a toothed segment. Each 80 lever is controlled by a spring 63, 62, 61 and 60 respectively which pulls back the lever from the electromagnet after it has been attracted. To the lever 56 is connected a rod 64 which is arranged across the levers 57, 85 58 and 59, so that when any one of these three levers moves, the lever 56 is also caused to move. The toothed segments of the levers 56-59 engage with toothed rolls 65-68 the end faces of which are arranged obliquely 90 of the axis, so that the rolls have a wedge-shaped form. The toothed segments of the levers 56-59 are in length equal to half a circumference of the toothed wedge-rolls so that each of the rolls can be turned by the 95 corresponding lever only to the extent of 180°. Alternately with the toothed rolls are arranged plain rolls 69, 70, 71, 72 and 73, mounted on the fixed spindle 74, which carries the toothed rolls so as to be able to slide 100 but not to rotate thereon say by a pin or bolt 74' secured to each of the said smooth rolls, and engaged in a groove on the spindle 74. The toothed rolls are, on the contrary, both 105 movable endwise and rotatable on the spindle. Owing to the wedge-shaped form of the rolls, their greatest length is directly opposite their shortest. The rolls are arranged next to each other in such manner that the shortest length of the toothed rolls, and the 110 greatest length of the smooth rolls are coincident. In front of the rolls, a member 75 is movably mounted on the spindle 74, and to this member is connected an arm 76 effecting the advancing of the bars 24, and the 115 core 75' of a coil 47 which is arranged within a helical spring 75'' which returns the body 75 to its original position after movement. The driving arm 76 is provided with a pin 76' engaging in an elliptical groove 78' of a cam 120 78 mounted on a rotatable spindle 77 on which is mounted a ratchet wheel 79 having four teeth. With the ratchet wheel engages a spring-controlled pawl 80 with which 125 operates a second pawl 81 secured to the member 75. When the levers 56-59 are rocked by their armatures being attracted by the corresponding electromagnets, they turn the toothed wedge-rolls 65-68 to the extent of 180°, so that the greater lengths of 130

the toothed rolls coöperate with those of the smooth rolls, and the whole system of rolls is moved, together with the member 75, along the spindle 74. In this way, the driving arm connected to the body 75, acts on that one of the bars 24 which is in front of it, and causes it to move to an extent corresponding to the movement of the system of the rolls.

10 When the current of the electromagnets is cut off, the levers 56—59 are pulled back into their normal position by their springs 60—63, the toothed rolls are turned back, and the whole system brought to its original 15 position. At the same time, the member 75 is pulled back into its original position by its spring 75''. The spring-controlled pawl 80, engaging with the ratchet wheel 79, turns the said wheel when moved with the member 20 75, and also the cam 78 through an angle of 90° whereby the smaller axis of the elliptical groove 78' comes into vertical position and the driving arm 76 is lowered, so that it is opposite the downwardly bent end of the 25 next bar 24. At the next operation of the system of rolls, another turning of the cam 78 through an angle of 90° takes place, whereupon the large axis of the elliptical groove comes into vertical position, and the driving 30 arm is again raised, so that it is opposite the upwardly bent end of the next bar 24. In this way, the driving arm not only effects a reciprocating movement, but also alternately rises and falls in accordance with the ends of 35 the bars 24, alternately bent up and down. To make sure of the return of the member 75, it is controlled not only by a spring 75', but also by a coil 47. In that coil the current is cut off at a later moment than in the electromagnets A—D, so that the coil attracts the iron core connected to the member 75, and the member is brought back even if the spring 75' should fail to act. The turning of 40 one of the toothed wedge-rolls results in a 45 movement of all the rolls arranged in front of it, to the extent corresponding to the difference between the longest and the shortest lengths of the corresponding wedge-roll. These differences amount for the toothed 50 rolls 65, 66, 67, 68 in the construction illustrated by way of example to 16, 8, 4 or 12 millimeters. But as no one of the rolls 68 67 66 is turned alone, but, owing to the action of the transverse arm 64 connected to the lever 55 56, the roll 65 is also caused to turn, movements of $16 + 12 = 28$, $8 + 12 = 20$, $4 + 12 = 16$ and 12 mm. (when the roll 65 turns alone) can be obtained. When two rolls are simultaneously turned, and the roll 65 also caused 60 to turn, that is to say, when the rolls 68, 67, 65 or 68, 66, 65, or 67, 66, 65 are simultaneously operated, the movements will be equal to $16 + 8 + 12 = 36$ mm., $16 + 4 + 12 = 32$ mm., and $8 + 4 + 12 = 24$ mm. Finally, when all 65 the three rolls are turned simultaneously,

and the fourth caused to turn too the roll system will be moved to the extent of $16 + 8 + 4 + 12 = 40$ mm. With this system of rolls, it is therefore possible to obtain, by means of the stated rotations of the wedge- 70 rolls, movements of 40, 36, 32, 28, 24, 20, 16 and 12 mm.

The electromagnets A, B, C are intended for raising blue, yellow or red pile threads and their combinations, while the electromagnet D starts the raising of the white threads. The electromagnets are arranged on a board 54 resting on two metal plates 50 and 51 supported by a frame 52 carried by means of rollers 53, on a fixed plate 48. On 80 the plate 50 are arranged insulated contact pins $a^1, a^2, b^1, b^2, c^1, c^2, d^1, d^2$ and f^1, f^2 which are connected by means of wires to the electromagnets A, B, C, D and to the coil 47 respectively (Figs. 4, 5 and 27), and supply current 85 when, by touching the contacts of a plate 46 arranged under the pins on the plate 48, they close the circuit into which the electromagnets or the coil 47 are switched. The board 48 is arranged on standards 49, (Fig. 1—3) 90 in such manner that it can be adjusted to an exactly horizontal position. The plate 46 provided with contacts (Fig. 18) can be made in various ways, for instance, by stamping out a sheet-metal plate at the places intended for the contacts, etching the surfaces between them and coating them with glass or some other insulating material. The surface is thereupon ground, and the sheet-metal plate secured to a suitable backing or 100 support. Or the contact plate may be made by cutting out of a sheet-metal plate the parts which are to be non-conducting, and filled these perforations with some insulation material. To the contact points are 105 connected conductor wires which are joined together into a cable, and connected to the wires connected to the contact pins of the transmitter plates.

The frame 52 carrying the receiver, is secured to a rod 82 and can move to the left and to the right (Figs. 2 and 3) as the rod 82 is caused to move by a rod 83 which is reciprocated by a rocking lever 84. At the end of the rod 83 are provided two projections 83' 115 with a corresponding intermediate space, in which engages the upwardly bent end of the rod 82. By this construction the rod, and therewith the contact plate 46 are not caused to move, at the commencement of a movement of the rod 83, but the rod 83 has a certain advance of movement over the rod 82, the extent of the said advance being adjustable as the space x can be increased or lessened by means of a set screw 83''. The rod 120 83 carries a contact bar 85, the contacts of which have an advance relatively to the contacts of the plate 46, to the extent of half a contact, so that the contact on the bar 85 is covered by the corresponding contact pins 125 130

86 earlier than that of the plate 46. The contact bar 85 can be made in the same way as the plate 46. The diagrammatic drawing in Fig. 19 shows clearly the arrangement of 5 the contacts of the bar 85 and of the plate 46 relatively to the position of the bars 24. The contact pins belonging to the bar 85, are connected to a source of current B' (Fig. 13). The lever 84 is oscillated by a reciprocating 10 rod 90 provided with pins 90' which contact with the circumference of a heart-shaped or other cam 87, so that when the cam rotates the rod executes a longitudinal reciprocating movement which it transmits to the lever 84. 15 The cam 87 is mounted on a spindle 87' which carries a rope pulley 88 about which is wound a rope 89, which transmits the movement of the disk 88 to the driving pulley 89' of the mechanism required for the transmitter 20 plates (Fig. 13). The rope pulley 88 is driven by a crank rod 10, connected to the pin 10' of the bevel wheel 9 hereinbefore described, (Figs. 20 and 22). The contact pins 86 which make contact with the bar 85, are 25 mounted in a fork 92 which affords guidance to the rod 85 during its reciprocating movement.

The operating of the wedge roll system is effected by a device called the transmitter. 30 This device, as already stated, consists of three transmitter plates 127^a, 127^b and 127^c, which are arranged side by side in a common frame and electrically insulated from each other (Fig. 27), and carry respectively the 35 red, the yellow and the blue partial picture. On each plate only those points are conducting which correspond to the partial picture of the article to be reproduced, while the other points are non-conducting, as they are 40 covered with chromium oxid gelatin. On the plates slide three spring contact pins 128^a, 128^b, and 128^c, (Fig. 27) one on each plate. The contact pins have a common 45 guide. They are electrically insulated from each other and must move synchronously with the receiver, which is effected by the bar 85 driving the receiver, also driving the contact pins of the transmitter plates.

As already stated each of the three transmitter plates is connected to one pole of a 50 source of current. To the other pole are connected wires leading to the contact plate 46 (Fig. 27). Assuming that the first contact pin 128^a is in the center of the transmitter 55 plate carrying the red partial photograph, then the second and third contact pins are in the center of the transmitter plates for the yellow and blue partial photographs. Only the following cases are possible, (1) the center 60 of the transmitter plate for the red partial photograph is conducting, and the central points of the two other plates are non-conducting. (2) The center of the second plate is conducting, and that of the two other 65 plates non-conducting. (3) The center of the

third plate is conducting, and that of the two others non-conducting. (4) The center of the first and second plates are conducting, and that of the third plate non-conducting. (5) The centers of the first and third plates are 70 conducting, and that of the second non-conducting. (6) The centers of the second and third plates are conducting and that of the first non-conducting. (7) The centers of all the three plates are conducting and (8) the 75 centers of all the three plates are non-conducting. If, for instance, we had the first case, which means that the center of the object or picture, the partial one-color photograph of which in red is given on the first 80 transmitter plate and which in three-color printing is rolled with red ink, then, in order to reproduce this point, a red binding point must be produced in the fabric, that is to say, a red pile thread must be brought into the 85 upper shed. Owing to the contact pin coming into contact with the conducting center the circuit into which the contact pin is switched in, will be closed (Figs. 27 and 28). The current passes from the source of current 90 through the first transmitter plate 127^a, into the first contact pin 128^a, and from the latter into contact series III of the contact plate 46. Through the contact pin c² of the electro-magnet C, which touches one of the contacts 95 of the series III, the current passes through the windings of the electromagnet forming the bridge between the two contact series III and IV, through the contact pin c' of the electromagnet C into the contact series IV 100 which need not be interrupted, and thence to the source of current. The electromagnet C attracts the armature of the lever 57, the toothed sector at the end of which rotates the toothed wedge-roll 66, and at the same time 105 the roll 65, whereby the system of rolls with the driving arm 76 is moved to a corresponding extent (in the present case, to the extent of 4 + 12 = 16 mm.) The driving arm now 110 presses the bar 24 in front of it, and the blade passes in the corresponding column of hooks under the hook r which is connected a red pile thread.

When during the movement of the receiver, the contact of the electromagnet with the 115 contacts of the plate 46 is interrupted, the system of rolls again returns to its original position, and the member 75 carrying the driving arm, is withdrawn by the spring 75'. The spring 75' is assisted in its action by the 120 coil 47 which is connected to the source of current in a separate circuit. The ends of the coil wire are connected to the contact pins f' f'', the former of which is arranged above the contact series II, and the second above 125 the contact series I. The contact pin f'' is so arranged relatively to the contact pins of the electromagnets A, B, C that it is in advance of them to the extent of one contact, that is to say, in the beginning it is at the point of

interruption between two contacts, when a pin of the electromagnets A, B, C is at the edge of the contact. The consequence of this is that the current in the coil is cut off 5 later than that in the electromagnet. Consequently when the system of rolls returns to its original position the coil attracts the core 75" connected to the member 75 and causes the member with the driving arm to return, 10 even if the spring 75' should fail. If, when the contact pins of the electromagnets come into contact with the next contacts of the plate 46, the circuit is again closed, by the contact pin striking a conducting point of the 15 transmitter plate, then the receiver can act again. If for instance, we should have the case mentioned under 5, in which the centers of the red and blue plates are conducting, and the center of the yellow plate non-conducting, 20 that would mean that the corresponding point of the original reproduces red and blue points, that is to say, is violet. In three-color printing, such a violet point could be produced by the coincidence of red and blue 25 colored points. In the present case, in which the coincidence of colors or color subtraction cannot be utilized for which purpose violet threads are provided in the pile warp, a violet thread must be raised into the 30 upper shed. Owing to the contact of the contact pins 128^a and 128^c, the circuit is again closed, but it is now divided into two branches. One branch current will flow, like the whole 35 current before, through the windings of the electromagnet C, the other into the contact series VII of the contact plate 46, through the contact pin a' into the windings of the electromagnet a through the contact pins a" 40 bar VI and back again to the source of current. The two electromagnets A and C will therefore be simultaneously excited and thus the levers 59 and 57 simultaneously operated. The wedge roll system and the driving arm will be moved, and the said arm will therefore 45 bring the blade under the hook v, so that a violet upper pile warp thread will be lifted into the upper shed.

In the case 7 all the three colors are operative. In three-color printing, a black point 50 will be obtained by the coincidence of three colored points, but in this invention a black pile warp thread is raised. In the last case, in which no contact pin establishes a conducting connection, the circuit remains 55 broken and the electromagnets do not act on their levers. Only the circuit, into which is switched the electromagnet D, is closed by the contact of the pins d¹ d² with the contacts of the series I, II of the plates 46, and 60 the electromagnet D excited. The lever 56 is alone operated, and brings about a movement of the system of rolls and of the driving arm to an extent which is not sufficient to bring about a movement of the bars 24. 65 These latter remain in their normal position

in which the blades are below the hooks of the first series w to which are connected white pile warp threads. During the formation of the upper shed, a white pile thread will then be raised. For the rest, the movement and 70 turning of the driving arm 76 take place in exactly the same manner as if a colored thread were raised. The operation of the device for the transmitter is effected as already stated from the rope pulley 88 which 75 is positively connected by means of a rope 89, to a pulley 93 and drives the latter (Fig. 13). The pulley 93 is mounted on a spindle 94 on which are mounted rope pulleys 95 and 96 which transmit the movement 80 of the spindle 94 to the spindles 97' 98' by means of ropes and pulleys 97, 98. On the spindle 98' is mounted a heart-shaped or other cam 101 and a ratchet wheel 102 on which acts an escapement 99 operated by an 85 electromagnet 103. The electromagnet 103 is connected to the source of current B' into the circuit of which, as already stated, is also switched the contact bar 85. Whenever the pins 86 make contact with the contact bar 90 85, the circuit will be closed, the armature 99 of the electromagnet 103 attracted, and the ratchet wheel 102 caused to rotate to the extent of one tooth. If, on the contrary, the contact with the bar 85, and thus the 95 circuit, are interrupted, then the armature 99 of the electromagnet is returned by its spring 104 to its original position. The cam 101 reciprocates a bar 105 the latter being 100 provided with rollers, pins or the like engaging with the outer circumference of the cam. The rod or bar 105 acts on a bar 106 which is slotted longitudinally and is rotatably mounted at its end 106'. The rod 106 is connected to a rod 107 provided with holes 105 by means of a bolt 108 passing through one of the holes in the rod 107 and through a slot in the rod 106. With the rod 107 engages a rod 109 which carries contact pins for the 110 transmitter plates and causes them to move. The length of the arm between the connection point of the bars 109 and 107 and that of the bars 107 and 106, can be altered to correspond with the extent of movement of the 115 contact pins of the transmitter plates, and the desired fineness of the picture. Two pins 110 and 111 are provided on the side of ratchet wheel 102 which pins come into contact with the wire of a battery B² once at each half revolution of the ratchet wheel. 120 In the circuit of this battery is an electromagnet 113 which operates a lever 112 which, when the current is cut off, is held fast in its normal position by means of a pressure spring 114 acting against the end of 125 the lever. The escapement 112 operates a ratchet wheel 115, to the spindle 97' of which is secured a split nut 116 by means of a bolt 116' (Figs. 15-17). With the nut 116 engages the screw-threaded end of an adjust- 130

able, but not rotatable, rod 135, to which is connected a slotted rod 117 rotatably mounted at its end and operating a rod 118 to give movement to the frame 119, of the transmitter plates. As transmitter plates of various sizes can be arranged in the frame 119, it is necessary to be able to alter the size of the upward movement and for this purpose the rod 118 is provided with a number of holes, so that it can be connected to the rod 117 at different distances from its end. For plates of the greatest height, that the frame can take, the pin 131 connecting together the rods 117 and 118, must move up to the level 15 of the perforation 132. When the transmitter plate is half as high, the path to be traveled must be half as great, in which case the connecting bolt 131 is engaged in the hole 133 and through the slot of the rod 117, in order to move the pin from the position 20 marked 133 into that marked 134, (Fig. 13).

As each transmitter plate is, for instance, divided into 1,000 points in each row, a transmitter plate must be moved $\frac{1}{1000}$ part 25 of one row to correspond, and the ratchet wheels 115 must be made accordingly, in order to enable the rod 117 with the nut 116 to be moved to the extent desired. In the construction illustrated, the spindle 97' is 30 provided with thirteen different ratchet wheels, and corresponding lever escapements are provided, in order to enable transmitter plates of various heights to be mounted in the frame. The lever escapement corresponding 35 to the ratchet wheel used, is switched into the circuit of the battery B².

If only one contact pin had to travel over the whole width of the corresponding transmitter plate, the loom would work too 40 slowly and for this reason, in practical working several contact pins are used for each plate. In the construction illustrated, 10 contact pins are to be used for each transmitter plate. There must, therefore, be as 45 many receivers above the contact plate 46. Each transmitter plate is divided into 10 equal parallel strips insulated from each other (Figs. 10—12), and each part of the transmitter plate is provided with a separate 50 pin insulated from the others. To that end, the perforations of the rod 109 through which the pins pass, are lined with bushes of insulating material. Each part of the transmitter plate is provided with a separate conductor connected to one pole of the source of current. The first, third, fifth and seventh 55 series of contacts are divided into as many equal portions as there are pins sliding over each transmitter plate (Fig. 18). The connection 60 between the sections of a series of contacts of the plate 46 with the contact pins of the transmitter plate, takes place in such manner that each section of the series of contacts receives separate wires. The un- 65 divided series of contacts of the plate 46 are

connected to the second pole of the source of current. The two series of contacts I, II (Fig. 27) are also connected directly to the source of current. The rod 109, carrying the contact pins, is arranged in a tube 124 supported in two bearings 123 (Figs. 8—12). On the pin rod 109, there is a projection 125 passing through a slot of the tube 124. The projection is provided with a slot, into which is introduced a bar 126 which can be fixed by 70 means of screws. Through the perforations of the bar 126 pass the contact pins 128 which are held fast in the bar by means of set screws. Before the loom is started, the frame 119 must be brought into its lowest 80 position. To that end, the nut 116 is disconnected from the rod 135 after withdrawing the bolt 131, and brought into the original position of the screw at the end of the rod 135, and the latter, with the lever 117, is set 85 in its lowest position. The bolt 131 is introduced into the hole of the rod 118, corresponding to the size of plate used, and the rod 113 connected to the rod 117. The escapement is set over the ratchet wheel corresponding 90 to the plate selected, and its electromagnet 113 connected to the source of current B², whereupon the transmitter plates 127^a, 127^b and 127^c are introduced into a frame 119, and a rod 109 corresponding to 95 the width of the plate or to the width of the sections of the plates, is introduced; the lever 106 is brought into its outermost position, and the corresponding hole of the rod 107 connected by a bolt 108 to the slotted 100 rod 106. The two cam disks 87 and 101 occupy their outermost positions shown in the drawings in Fig. 13. As the picture to be produced must be provided with an edge, there are provided in addition to the hooks 105 producing the picture, other hooks for the edge, which raise only threads of the ground fabric of one color. The pin rod 109 must first travel a distance corresponding to the edge of the frame, before the remainder of 110 the device becomes operative. The pin rod 109 is given an advance relatively to the receiver, this being attained by the rod 83 carrying the contact bar 85 not driving the rod 82 at once, but only when the end of the 115 rod 82 strikes the second projection 83' of the rod 83. The object of this advance is to make sure, that the conducting points of the transmitter plates are covered, when the raising device for the hooks becomes operative. As the distance of the conducting points is different for various sizes of plates, the extent of the advance can be modified by 120 operating the set screw 83".

When the countershaft of the spindle 1 is 125 driven, then the bevel wheel 9 rotates by means of the crank 10, the pulley 88 and thus the cam disk 87. In this way, the contact bar 85 and the receivers are moved, and the receivers operated. According to the 130

extent of movement of the system of rolls, the bars with the blades are moved to a corresponding extent, so that the blades come under the hooks to be raised. Whenever a 5 contact pin touches a conducting point of the transmitter plate, the system of wedge-rolls is moved, and one blade is set in a column of hooks. When the contact pins of the electromagnets arrive, during the movement of 10 the receiver, to a break between two consecutive contacts of a series of contacts of the plate 46, the current is cut off, the system of wedge-rolls returns to its original position, as 15 already described, the driving arm is withdrawn and simultaneously lowered or raised, so that it comes in front of the downward or upwardly bent end of the next bar, and becomes operative during the subsequent advance of the receiver, when the circuit is 20 again closed on the contact pins of the electromagnets touching the following contacts of the plate 46. In this way, the system of wedge-rolls becomes operative as often as the corresponding contact pin of the transmitter 25 plate comes into contact in its travel with conducting points. The movement of the contact pins is brought about by the movement of the pulley 88 being transmitted through the gear 89 and a suitable counter- 30 shaft, to the cam disk 101 which by the intermediate means described transmits the said movement to the rod 109 carrying the contact pins. At the same time, owing to the pins 86 of the contact bar 85 coming into 35 contact the circuit of the source of current B' is alternately closed and opened, whereby the ratchet wheel 102 is intermittently-released from the corresponding escapement, and the contact pins are intermittently 40 moved. By means of the contacts 110 and 111 on the ratchet wheel 102, the circuit of the source of current B'' is closed once at each half revolution, so that the ratchet wheel 112 is released, and the spindle 97' can 45 turn, while during the remaining time the belt or rope slips on the driving pulley 98. When the spindle 97' is rotating, the nut 116 is driven and thus gives the frame 119 the required feeding movement.

50 As soon as the cam disk 87 has completed half a revolution, its movement, and that of the parts driven by it, stop as the bevel wheel 9 makes only half a revolution, the wheels 4 and 6 becoming disengaged. At 55 the same time, the wheels 5 and 7 come into engagement, the spindle 11 of the loom becomes operative and the batten swings back from the cloth beam. The treadle to which is connected the rod 12, is operated by a suitable gear from the spindle 11 of the loom. The rod 12 rocks the lever 13 which produces the upper and bottom sheds. As there is an intermediate space between the blades and the hooks the latter cannot follow the movement at once. This time is utilized for seiz-

ing the bars already brought into the corresponding position, by means of bar 29 provided with a cutting edge and for securing their position during further movement. When upper and bottom sheds are formed, 70 the weft and the wire are thrown in simultaneously in the well-known manner the batten goes back to the cloth beam and the raised portions are again lowered. After all the hooks have reached the bottom board the 75 bars come to rest a little later for they have still to travel the path required in order to reach the distance indicated between the blades and the hooks. This time is utilized in order to push the bars back in the manner 80 described by means of the board 33, in order that they should come back again into their original position. The engagement of the wheels 5 and 7 then comes to an end, but the wheel 4 again comes into engagement with 85 the wheel 6, so that the process described is repeated again in the same way, only the pin rod and receiver go back and the bars are set from the other side.

Having now particularly described and ascertained the nature of my said invention and in what manner the same is to be performed, I declare that what I claim is:

1. The combination, with a plurality of transmitter plates each forming a circuit-making and breaking device, electro-magnets corresponding to said plates, a source of current, circuit connections between the magnets, the current source and the plates, each plate controlling a definite magnet, a 100 part to be moved different distances, armatures actuated by the magnets, mechanism for transmitting the individual movement of each armature to said part, and means for causing said mechanism to transmit to said 105 part the sum of the movements of any two or more armatures simultaneously actuated by their magnets, substantially as described.

2. The combination, with a plurality of transmitter plates each forming a circuit-making and breaking device, electro-magnets corresponding to said plates, a source of current, circuit connections between the magnets, the current source and the plates, each plate controlling a definite magnet, a 110 part to be moved different distances, armatures actuated by the magnets, mechanism for transmitting the individual movement of each armature to said part, means for causing said mechanism to transmit to said 115 part the sum of the movements of any two or more armatures simultaneously actuated by the magnets, and a moving support carrying said part and controlling the making and breaking of the circuit by said plates, 120 substantially as described.

3. The combination, with a plurality of circuit-making and breaking devices, of a part to be moved different distances, separate electro-magnetic means respectively 130

controlled by said devices, and separate mechanism, respectively controlled by said electro-magnetic means, adapted each to move said part a given distance, said mechanisms being also coöperative, upon simultaneous actuation of any two or more of them, to move said part a greater distance than it is moved by any one of said mechanisms, substantially as described.

4. The combination, with a plurality of circuit-making and breaking devices, of a part to be moved different distances, a suitable support carrying said part and guiding the same, separate electro-magnetic means, respectively controlled by said devices, separate armature levers respectively controlled by said electro-magnetic means, alined rotary parts arranged in said support and controlling the part to be moved, said parts having their adjoining faces cut at an angle to their axis of rotation and being respectively controlled by said armature levers, and a bar carried by one armature lever and extending over the other, substantially as described.

5. The combination, with the frame, the rows of hooks and the hook-raising and lowering means of a jacquard machine, of a sliding device appropriated to each row of hooks and carried by said hook-raising and lowering means and movable thereon lengthwise of the corresponding row of hooks, said device being adapted to engage and support any one hook in the corresponding row, a plurality of circuit-making and breaking devices, a suitable support, a receiver movable on said support transversely of the sliding devices and comprising a suitable movable part adapted to actuate each device, separate mechanisms adapted each to move said part a given distance, and electro-magnetic means respectively controlled by said circuit-making and breaking devices and respectively controlling said mechanisms, said mechanisms being also coöperative, upon simultaneous actuation of any two or more of them, to move said part a greater distance than it is moved by any one of said mechanisms, substantially as described.

6. In a receiver mechanism, the combination of a part to be moved different distances, a fixed shaft on which said part is guided, alined devices arranged to slide on said shaft and thereby move said part, said devices having their end faces arranged at an angle to the axis of said shaft and alternating ones thereof being rotary and the remainder non-rotary, and means for rotating said rotary devices individually, substantially as described.

7. In a receiver mechanism, the combination of a part to be moved different distances, a fixed shaft on which said part is guided, alined devices arranged to slide on said shaft and thereby move said part, said devices having their end faces arranged at an angle to the axis of said shaft and alternating ones thereof being rotary and toothed and the remainder non-rotary, levers having toothed portions engaging said toothed devices, means for actuating the levers individually, and a bar carried by one lever and extending over the others, substantially as described.

8. The combination of a series of interrupted and continuous contacts, a carriage movable over said contacts, electro-magnets carried by said carriage and each having one pole thereof electrically engaged with one of the continuous contacts and the other pole thereof electrically engaged with one of the interrupted contacts, a part to be moved different distances carried by said carriage, mechanisms, controlled by said magnets and also carried by said carriage, for actuating said part, a source of electric energy having one pole connected with each of the continuous contacts and the other connected with the interrupted contacts, and circuit-making and breaking devices operative upon movement of the carriage, substantially as described.

In testimony whereof, he affixes his signature, in presence of two witnesses.
